UNITED STATES PATENT OFFICE.

FRANK MOSSBERG, OF ATTLEBORO, MASSACHUSETTS, ASSIGNOR TO MOSSBERG
PRESSED STEEL CORPORATION, OF ATTLEBORO, MASSACHUSETTS, A CORPORA-
TION OF MASSACHUSETTS.

BEAM HEAD.

Application filed October 8, 1920. Serial No. 415,587.

To all whom it may concern:

Be it known that I, FRANK MOSSBERG, a citizen of the United States, residing at Attleboro, in the county of Bristol and State of Massachusetts, have invented certain new and useful Improvements in Beam Heads, of which the following is a specification.

This invention relates to an improvement in the construction of beam-heads in which the head is adapted to be adjustably connected to a beam on which yarn or other material may be wound, and the object of this invention is to provide a head for beams of this character which is preferably constructed of sheet metal and which is provided with a hub-member adapted to be readily contracted to bind the head in adjusted position upon the beam.

10 The nature and advantages of the invention will be better understood when the following detail description is taken in connection with the accompanying drawings, the invention residing in the combination and arrangement of parts as claimed.

In the drawings forming part of this specification, like numerals of reference indicate similar parts in the several views and wherein:

30 Figure 1 is a side elevation illustrating my improved beam-heads as applied to the ends of a beam.

Figure 2 is an end view of my improved beam-head.

35 Figure 3 is a section on line 3—3 of Figure 2 illustrating the clamp by which the hub-section is adjustably connected to the head-plate.

With reference to the drawings, 10 designates the usual body portion of a warp beam which in this particular case is usually constructed of wood, but which, of course, may be made of any desired material.

40 In the making of a beam of this character the head members 11 are preferably so constructed that they may be adjusted along the length of this body portion so as to regulate the working width of the beam.

45 It is also one of the objects of this invention to construct both the head-plate and the hub-portion of sheet metal whereby the head may be very light in weight and the hub sufficiently yieldable to be readily con-

tracted to clamp the same upon the body portion and hold the head in any adjusted position thereon.

The following is a detailed description of one construction of beam-head by which this result may be accomplished:

The main plate 12 of this head is preferably formed of sheet metal and its peripheral edge is bent or folded to provide a stiffening flange 13 and the center of this plate is usually cut out as at 14 to permit the passage of the beam or body portion therethrough. A hub member 15 is connected to the outer face of each of these plates, which hub is preferably formed of sheet stock usually of a greater thickness than that of the head-plate, and this hub is preferably made in four sections 16, the ends 17 of each section being bent to extend outwardly providing radiating arms, the outer ends of the adjacent arms of the adjacent sections being turned inwardly and are fulcrumed one against the other, and the inner portions of these adjacent arms are normally spaced apart as at 19 and a bolt 20 is passed therethrough and the nut 21 when set up draws the adjacent sections toward each other causing the hub sections to contract about the body 10 to grip and bind the same and hold the head thereon in adjusted position.

80 The middle portion of each hub section is adjustably secured to the head-plate by the clamp member 22 which is shown in Figure 3, the neck portion 23 of which extends through the corresponding opening 90 through the side wall of the hub, and the body of this clamp is riveted as at 27 to the head-plate thereby permitting the hub-section to slide radially thereon.

85 The outer ends of these radiating arm members 17 may be connected to the head-plate by means of bolts 25 if desired or in some cases, particularly where the head-plate itself is split as at 26, the arms 27 on opposite sides of the split portion may be connected to its section of the plate by rivets 28, whereby the head-plate itself may be slightly separated if desired thereby providing a greater range of adjustment whereby the head itself may be contracted about 100 the beam or body portion.

105 Where the head-plate is formed in sections I preferably provide guide fingers 29

on each part of the plate to hold the plate sections in alinement or in the same plane with each other.

By the use of my improved construction 5 of beam-head, I am enabled to do away with the usual heavy and cumbersome cast-iron hub which heretofore has been employed for this purpose and have provided one which is much lighter in weight, less expensive to 10 construct, is stronger, and more durable and by its use this hub may be readily contracted to a comparatively increased extent to grip and bind the body portion of the beam and hold the head in adjusted position 15 thereon.

The foregoing description is directed solely towards the construction illustrated, but I desire it to be understood that I reserve the privilege of resorting to all the 20 mechanical changes to which the device is susceptible, the invention being defined and limited only by the terms of the appended claims.

I claim:

25 1. A beam-head comprising a main disk-plate, a contractible hub member comprising a plurality of sections each formed of a strip of yieldable material set edgewise against said plate and adjustably connected 30 thereto, each section of said hub member being provided with a pair of radiating arms one at either end thereof fulcrumed at their outer ends and normally separated at their inner ends, an independent member on said 35 plate intermediate said arms adjustably

connecting each strip segment to said plate, and means acting on said arms to contract said hub about the beam.

2. A beam-head comprising a main disk-plate, a sectional contractible hub member 40 adjustably connected to said plate, said hub comprising a plurality of sections formed of a strip of yieldable material set to slide edgewise on said plate, each section of said hub being provided with a pair of radiat- 45 ing arms, the adjacent arms of the adjacent sections being fulcrumed at their outer ends and normally spaced apart at their inner ends, means located intermediate said arms for adjustably connecting the different sections to said plate, and a bolt mounted to 50 act upon and move said arms to contract said hub about the beam.

3. A beam-head comprising a main disk-plate formed in sections, each section being 55 formed of a strip of yieldable material set edgewise to slide on said plate and each having a pair of radiating arms and adjustably connected to said plate sections, clamping means in said arms for contracting both 60 the hub sections and plate sections about the beam whereby the head may be held in adjusted position thereon, means located intermediate 65 said arms for adjustably connecting each section to the plate, and means for supporting said plate sections in alinement.

In testimony whereof I affix my signature.

FRANK MOSSBERG.
